UNITED STATES PATENT OFFICE

168,270

CHAISE LONGUE

Walter F. Lamb, Honolulu, Territory of Hawaii

Application January 12, 1952, Serial No. 18,026

Term of patent 14 years

(Cl. D15—11)

To all whom it may concern:

Be it known that I, Walter F. Lamb, a citizen of the United States of America, residing at Honolulu, Island of Oahu, Territory of Hawaii, have invented a new, original, and ornamental Design for a Chaise Longue, of which the following is a specification, reference being had to the accompanying drawing, forming a part hereof:

Fig. 1 is a top plan view of a chaise longue showing my new design.

Fig. 2 is a side elevational view.

Fig. 3 is a bottom plan view.

Fig. 4 is an end elevational view.

I claim:

The ornamental design for a chaise longue, as shown.

WALTER F. LAMB.
